UNITED STATES PATENT OFFICE

ROY F. ANDERSON, OF DETROIT, MICHIGAN, ASSIGNOR TO THE MURRAY CORPORATION
OF AMERICA, A CORPORATION OF DELAWARE

RUBBER DOOR BUMPER

Application filed March 4, 1932. Serial No. 596,735.

This invention relates to resilient bumpers for cushioning the contact of door edges with door casings and the connection and assembly of such bumpers to the door post or door casing.

6 An object of the invention is to provide a door post with a bumper-receiving socket and a bumper which may be applied to the socket by a simple insertion therein, and securely locked therein by a partial rotation of the bumper in the socket.

10 Another object of the invention is to provide a bumper and a socket in a door post of special construction adapted to cooperate 15 for efficient tension and easy assembly.

The above being among the objects of the present invention, the same consists in certain features of construction and combination of parts to be hereinafter described with 20 reference to the accompanying drawing and then claimed, having the above and other objects in view.

In the accompanying drawing which illustrates suitable embodiments of the present 25 invention and in which like numerals refer to like parts throughout the several views—

Figure 1 is a fragmentary perspective view, of a door post equipped with a buffer constructed in accordance with my invention. 30 Fig. 2 is a fragmentary perspective view of the construction of the door post shown in Fig. 1 with the buffer removed therefrom.

Fig. 3 is a fragmentary perspective view 35 of a door post having a buffer therein disposed in position, disclosing the first step in assembling the buffer to the door post.

Fig. 4 is a sectional view of the invention disclosing a buffer secured in position, taken substantially along line 4—4 of Fig. 1.

40 Fig. 5 is a sectional view of the invention taken substantially along line 5—5 of Fig. 2.

Fig. 6 is a plan view of a buffer constructed in accordance with my invention.

45 Fig. 7 is a sectional view of the buffer disclosed in Fig. 6, taken substantially along line 7—7 of Fig. 6.

Fig. 8 is a sectional view of the buffer disclosed in Fig. 6, taken substantially along line 8—8 of Fig. 6.

50 Heretofore buffers in the door jamb have

been secured therein by means of a screw or the like or a cover plate, or they were inserted in the socket provided therefor by greatly compressing the buffer and forcing it into the socket and reliance placed in resiliency of the buffer to maintain it in place. 55

When employing the present invention in connection with doors of motor vehicle bodies the door post 11 may be provided with a rabbeted edge portion 12, having surfaces 13 and 14, and a jamb face portion 15. The 60 edge of the door 10 is provided with corresponding surfaces.

As shown in Fig. 2, the door post is provided with a socket 16, open at the jamb face 15 and rabbet face 14, and which is defined by the cylindrical wall 17 and flat wall 22 of a metal stamping which has lateral flanges secured to the rear face of the jamb face 15 by welding or otherwise. A flange 18, formed 65 by the edges of the jamb face 15 around the opening therein, extends inwardly around the edge of the socket at the jamb face 15. 70

The opening in the rabbet face 14 is substantially less in length than the diameter of the cylindrical backing piece 17—22. A 75 buffer element 23 of any resilient material, but preferably a rubber block, is formed and secured in the socket 16, as hereinafter explained. The buffer 23 is formed with an undercut flattened edge portion 25, arcuate edge portions 26 at each end of the flattened edge and a reduced arcuate edge portion 27 opposite the flattened edge 25. This reduced arcuate edge portion 27 may be provided with a flat 80 edge face if desired. The maximum width of the block taken parallel to the flattened edge 25 is substantially equal to the diameter of the socket 17—22 taken parallel to the rabbet 85 face 14. 90

This block is provided with a circumferential groove 31 which follows the arc of the reduced arcuate edge portion 27 except along the flattened edge 25, through which it extends in a straight line at a depth, relative 95 to the edge 25, substantially equal to the depth of its arcuate portions relative to the edges 26. This groove 31 is adapted to receive the flange 18 as hereinafter explained.

As best shown by Figs. 1 and 2, the opening 100

in the rabbet face 14 is defined by edges 19 and 20, and the latter edge projects beyond the adjacent extremity of the cylindrical wall 17 extending into the opening, thereby providing a lip or shoulder.

In assembling to the door post the buffer is inserted endwise through the opening in the rabbet face 14 with the flattened surface 25 and the reduced arcuate edge 27 facing the edges 19 and 20 respectively of the opening as shown in Fig. 3. The block is then shoved into the socket in a straight line, with the flange 18 entering the groove 31 along the flattened edge 25, until one of the arcuate ends 26 strikes the wall 17 opposite the opening in the rabbet face 14, and is then given a quarter turn to rotate the outwardly extending end 26 into the socket behind the flange 18, which follows the groove 31, and to bring the reduced arcuate portion 27 into its projecting position in the rabbet as shown in Fig. 1. The block is thus locked in the socket against movement perpendicular to the jamb face 15 by the flange 18 engaging the grooves 31 along the arcuate edge portions 26, and from movement perpendicular to rabbet face 14 by the bearing of the arcuate edges 26 against the converging walls 17 adjacent the opening, as the maximum width of the block taken parallel to the flattened edge 25 is substantially equal to the diameter of the socket 17—22 taken parallel to the rabbet face 14.

The lip 20 serves as a limiting stop to such turning movement of the buffer by engaging the adjacent shoulder 28 of the latter, and also conceals the shoulder. If desired, the other edge 19, instead of edge 20, may be provided with the lip and in this event, the buffer would be positioned vice versa of that described above, in inserting it. Preferably in actual practice the lip will be located at the upper edge, because it will conceal the upper shoulder 28 of the buffer which otherwise would be more readily seen by observers. However, if desired slight lips may be provided at both edges 19 and 20 of the opening in the rabbet face 14 which will engage the shoulders 28 on the edge of the block at each end of the reduced arcuate portion 27, to assist in retaining it in the socket.

The face 24 of the block projects beyond the jamb face 15 and its edges 30 cover the edges of the socket opening, which provides a neat appearance. These overlapping edges 30 of the face 24 are not essential to the operation and efficiency of the buffer, however, and may be dispensed with if desired.

To remove the buffer from the socket it is rotated until it again assumes the position shown in Fig. 3 and then withdrawn in a straight line through the opening in the rabbet face 14.

From the foregoing description it is apparent that I have provided a buffer that is easily assembled and removed relative to the

door post and one that will not be dislodged in use.

While I have shown in the drawing a particular illustrative view of my invention and have described the elements and functions thereof in detail, various modifications may be made in the same and formal changes may be made in the specific embodiments of the invention described without departing from the spirit or substance of the broad invention, the scope of which is commensurate with the appended claims.

I claim:

1. In a doorpost having a jamb face and an angularly disposed rabbeted face contiguous thereto, said post having a circularly walled socket behind said faces, said faces having openings in said socket, the walls of said socket set back relative to the edges of the openings in said faces, a bumper block having a maximum width corresponding with the diameter of said socket and so formed whereby said block may be inserted into said socket through said rabbeted face opening with its flat side perpendicular thereto and then locked by rotation bringing the line of its maximum width parallel to the length of said rabbeted opening.

2. In a doorpost having a jamb face and an angularly disposed rabbeted face contiguous thereto, said post having a circularly walled socket behind said faces, said faces having openings in said socket, the walls of said socket set back relative to the edges of the openings in said faces, a bumper block having a maximum width corresponding with the diameter of said socket, a door engaging portion extending outwardly from and at right angles to the line of said maximum width, and so formed whereby said block may be inserted into said socket through said rabbeted face opening with its flat side perpendicular thereto and then locked by rotation bringing the line of its maximum width parallel to the length of said rabbeted opening.

3. In a doorpost having a jamb face and an angularly disposed rabbeted face contiguous thereto, said post having a circularly walled socket behind said faces, said faces having openings in said socket, the circular walls of said socket being perpendicular to said jamb face and set back relative to the edges of the openings, and cut along a minor arc at said rabbet face opening, a bumper block having a body portion, the maximum width thereof corresponding with the diameter of said socket, door engaging portions extending from the body at right angles with respect to each other, the maximum width of said bumper corresponding with the diameter of the socket and another width thereof being slightly less than the length of the rabbet face opening, and a continuous groove around said body portion adapted to receive

the edges of said jamb face opening, whereby said block may be inserted into said socket through said rabbet face opening and then locked by rotation bringing the line of its maximum width parallel to the length of said rabbet face opening.

4. In a doorpost having a jamb face and angularly disposed rabbeted face contiguous thereto, said post having a circular walled socket behind said faces, said faces having openings to said socket, the circular walls of said socket being set back relative to the edges of the openings and cut along a minor arc at said rabbet face opening, a bumper block formed for endwise insertion in said socket, said bumper having side and end door engaging portions disposed at right angles with respect to each other, said portions adapted to extend beyond the openings in said post, said bumper having a width slightly less than the length of the rabbet face opening, whereby said block may be inserted into said socket through said rabbet face opening and then locked by rotation bringing the line of its maximum width parallel to the length of said rabbet face opening.

5. In a doorpost having a jamb face and an angularly disposed rabbeted face contiguous thereto, said post having a circularly walled socket behind said faces, said faces having openings to said socket, the circular walls of said socket being perpendicular to said jamb face and set back relative to the edges of the opening in the latter, and cut along a minor arc at said rabbet face opening, a bumper block having a maximum width corresponding with the diameter of said socket, rounded side edges, a straight edge between said rounded edges and a continuous groove along said straight and rounded edges adapted to receive the edges of said jamb face opening, whereby said block may be inserted into said socket through said rabbet face opening with its flat side perpendicular thereto and then locked by rotation bringing the line of its maximum width parallel to the length of said opening.

6. In a doorpost having a jamb face and an angularly disposed rabbeted face contiguous thereto, said post having a circularly walled socket behind said faces, said faces having openings to said socket the circular walls of said socket being perpendicular to said jamb face and set back relative to the edges of the openings and cut along a minor arc at said rabbet face opening, a bumper block having a maximum width corresponding with the diameter of said socket, rounded side edges on said bumper, a straight edge between said rounded edges, a curved surface on the bumper diametrically opposite said straight edge, said curved surface terminating in straight surfaces adjacent, one end of the rounded side edges and a continuous groove along said straight and rounded edges adapt-

ed to receive the edges of said jamb face opening, whereby the block may be inserted into said socket through said rabbet face opening with its flat side perpendicular thereto and then locked by rotation bringing the line of its maximum width parallel to the length of said opening.

7. In combination, a door post having a jamb face and angularly disposed rabbeted face contiguous thereto, said post having a substantially circular walled socket behind such faces, said rabbeted face having an opening communicating with said socket, at least one edge of the opening extending toward the opposite edge thereof a distance to provide a lip at the adjacent extremity of the circular wall of the socket and a bumper block formed for endwise insertion in the socket through the opening in the rabbeted face and having a shoulder adapted to engage the lip, said block being so formed that it can be turned after such endwise insertion, and the shoulder brought into engagement with the lip.
